TIME SWITCH

Frank Conrad, Wilkinsburg, Pa., assignor to Westinghouse Electric & Manufacturing Company, East Pittsburgh, Pa., a corporation of Pennsylvania

Application October 15, 1935, Serial No. 45,043

7 Claims. (Cl. 200—36)

My invention relates to astronomical time switches and more particularly to switches of this character which control electric circuits and which automatically adjust themselves for different "on" and "off" periods in accordance with the variations in the length of daylight at different seasons of the year.

One object of my invention is to provide an astronomical time switch which may be easily and inexpensively manufactured, installed and maintained in operation.

Another object is to provide an astronomical time switch for turning on and off electric lamps or other devices in the evening and in the morning which may be easily and quickly set or adjusted to turn the lamps on at any desired time after sunset and to turn them off at any desired time before sunrise.

Another object is to provide an astronomical time switch which may be easily set or adjusted to turn on a circuit at any desired time after sunset and to turn it off at any predetermined time regardless of the time of sunrise.

Heretofore it has been necessary to design astronomical switches for the particular latitude of the country in which they are to be used. For instance, a switch designed for use in a section of the country falling in say latitude 40 will not operate accurately in a section of the country falling in latitude 30. This presented difficulties in the manufacture and sale of such switches in that if they were to be carried in stock for customers, it was necessary to manufacture and stock a large number of different designs, thus increasing the expense and also the opportunity for errors in carrying differently designed devices for supplying the demand from different sections of the country. Therefore, it is also an object of my invention to provide a switch for universal use and one which may be easily and quickly adjusted for use in any section of the country.

The invention itself, however, together with its additional objects and advantages, may be best understood from the following description taken in conjunction with the accompanying drawings, in which,

Figure 1 is a view, in front elevation, of an astronomical switch embodying my invention.

Fig. 2 is a view, in front elevation, of the instrument shown in Fig. 1 with the face plate and its supporting plate removed, (see lines II—II of Fig. 5);

Fig. 3 is a top plan view of the time switch shown in Fig. 1;

Fig. 4 is a view in side elevation (as seen from the right) of the time switch shown in Fig. 1;

Fig. 5 is a view taken on the line V—V of Fig. 1;

Fig. 6 is a view representing a vertical cross section through the means for setting the time switch to operate "Hours after sunset", taken along the line VI—VI of Fig. 2;

Fig. 7 is a top plan view of the switch operated by the timing mechanism shown in Figs. 1 to 5;

Fig. 8 is a top plan view of the levers for jointly controlling the operation of the time adjusting devices in accordance with the times of sunset and sunrise; and

Fig. 9 is a bottom plan view of the astronomical cam and its adjusting scale for controlling the time adjusting devices shown in Fig. 8.

Referring more particularly to the drawings, the time switch is provided with a frame comprising a base plate 1 upon which suitable corner posts 2, 3, 4 and 5 are mounted for supporting a central plate 6 and a top plate 7. The plates are held in a spaced apart parallel relation by the corner posts to provide supports in which the clock mechanism and time switch associated therewith may be mounted. The ends of the corner posts extend through the base plate and the top plate and a plurality of screw threaded nuts 8 are mounted thereon to hold the parts together. A face plate 10 is mounted upon the top plate and is spaced a short distance therefrom and parallel thereto by a plurality of spacing studs 11. The face plate 10 is provided with a dial 12 for the months of the year and a clock dial 13 for the hours and minutes of the day.

A calendar hand 14 is mounted upon a shaft 15 in position to be moved over the dial 12 by a clock mechanism 16 for indicating the month and the approximate day of the year when the switch is in operation. The divisions of the months are indicated on the dial by their first letters and the division for each month is separated into three sections so that the pointer will give an indication of the approximate day of the month as well as the month involved. A suitable knob 23 is disposed on the upper end of the shaft 15 for adjusting the calendar hand 14 to agree with the month and time of the month in which the instrument is operated.

An hour hand 17 and a minute hand 18 are disposed for operation over the dial 13 for indicating the time of day. The minute hand 18 is mounted upon and rotated by a shaft 20 and the hour hand is frictionally mounted upon a hollow shaft 21 rotatably disposed on the shaft 20. A suitable knob 22 is disposed on the outer

end of the shaft 20 for adjusting the minute hand and the hour hand to indicate the time of day accurately. The lower part of the dial 13 is marked with cross hatch lines to indicate approximately night time.

The calendar hand 14 rotates once a year, the hour hand rotates once each day and the minute hand rotates once every hour, therefore, when the device is in operation it will indicate to the observer the month, approximately the day of the month, and the time during the day.

Although any suitable motor may be used for driving the clock mechanism, I have illustrated a clock motor 24 for this purpose as comprising a toothed wheel 25 disposed on a shaft 33 having its ends supported in biasing blocks 34 and 35, a timing shaft 26 for driving the wheel 25, a pair of pole members 27 mounted on the timing shaft, and an electromagnet 28 for cooperation with the pole pieces in oscillating the timing shaft. A "hair spring" 26a is attached to the timing shaft for regulating its rate of operation. A contact making spring 29 is mounted on the post 2 and insulated therefrom for the purpose of making and breaking the circuit for the electromagnet 28 in accordance with the oscillations of the timing shaft 26. If desired, current may be supplied to the motor through a suitable copper oxide rectifier 30. Inasmuch as this motor does not constitute a part of the present invention, no further description of it is here given, but if more details are desired, they may be obtained from my copending application Serial No. 625,147, filed July 27, 1932 for improvement in Alternating-current direct-current clock.

A worm gear 37 is disposed on the shaft 33 in position to mesh with and rotate a worm wheel 38 and its shaft 39. A pinion 40 disposed on the shaft 39 drives the clock mechanism by rotating a gear wheel 42 on the shaft 20. Inasmuch as the minute hand 18 is mounted upon the shaft 20, it is driven around the dial 13 in accordance with the operation of the motor 24 and the chain of speed reducing gears 37, 38, 40 and 42. The gear wheel 42 is mounted upon the shaft 20 by means of a friction clutch 44, which permits adjustment of the shaft 20 and therefore the hour hand 17 and the minute hand 18 by operation of the knob 22 when it is desired to reset the clock.

The hour hand 17 is driven by the power of the shaft 20, through the medium of a chain of speed reducing gears comprising a pinion 46 on the shaft 20 meshing with a gear wheel 47 on a shaft 48 which operates a pinion 49 on its upper end above the plate 6 and rotates a gear wheel 50 which constitutes an integral portion of, and therefore, rotates the hollow shaft 21 upon which the hour hand is mounted. The hour hand is mounted on its shaft 21 by a friction collar (see Figs. 3 and 5) so that it may be adjusted relative to the minute hand. By reason of these speed-reducing pinions and gear wheels, it will be seen that the rotation of the shaft 20 by the motor 24 will effect a corresponding slower rotation of the shaft 21, so that the hour hand 17 thereon will travel once around the dial 13 each day while the minute hand 18 is making twenty-four revolutions each day and, therefore, that as long as the clock motor 24 is operating accurately and the minute and hour hands are properly adjusted the dial 13 will indicate the time.

The calendar hand 14 is also driven by the shaft 20 through a chain of speed reducing gears which cause it to be rotated once each year for indi-

cating the time of the year in months and fractions thereof. This chain of speed-reducing gears (Figs. 3 and 4) comprises (in addition to the pinion 46 on shaft 20 and gear wheel 57 on shaft 48), a pinion 53 mounted on and driven by the shaft 5 48 in position to engage and rotate a gear wheel 54 mounted on a shaft 55, a pinion 56 disposed on the shaft 55 in position to engage and rotate a gear wheel 57 disposed on a shaft 58, a pinion 59 disposed on the shaft 58 in position to engage 10 and rotate a gear wheel 60 disposed on a shaft 61, and a pinion 62 disposed on a shaft 61 in position to engage and rotate a gear wheel 63 mounted on the shaft 15. The gear wheel 63 is secured to the shaft 15 by friction clutch 64 to 15 permit adjustment of the calendar hand 14 independently of the gear wheel 63 by means of a knob 23 to any desired position.

The chain of speed reducing gear wheels 53, 54, 56, etc. just described is so designed that 20 accurate operation of the clock motor 24 will cause the calendar hand 14 to complete one rotation each year and thereby causes it to indicate on the calendar dial 12 the month and fraction thereof of the calendar year. It will also 25 be noted by the gear chains described, that operation of the motor 24 will drive the hour hand, the minute hand, and the calendar hand in such manner that any one may readily determine the month, the approximate day of the year and the 30 hour and minute of the day by observing the dials.

The time switch provided for operation by the clock mechanism is indicated by the numeral 70 and comprises a circuit-making cam member 71, 35 a cooperating brush 72, and a circuit-breaking cam 73 on a base member 74, (Figs. 5 and 7). The cam 73 and its base member 74 are rotatably mounted upon the shaft 21. A gear wheel 75 is mounted upon the upper end of the base member 74 and firmly affixed thereto by a circular nut 76 so that the cam 73 may be rotated on the shaft 21 by rotating the gear wheel 75.

The circuit-making cam 71 is provided with a hub 77 firmly affixed to an insulating bushing 45 78 which is rotatably mounted upon the body member 74 of the cam 73 so that the cams 71 and 73 may be rotated relative to each other. A shoulder 79 is disposed on the lower portion of the insulating bushing 78 to prevent electrical 50 connection at that point between the two cams. A gear wheel 82 is screwed upon the top portion of the bushing 78 and an insulating washer 81 is disposed between the wheel 82 and the cam hub 77 to prevent electrical connection therebetween. The gear wheel 82, the washer 81, the bushing 78, the hub 77 and the cam 71 are firmly locked together, so that the cam 71 may be moved relative to the cam 73 by rotation of the gear wheel 82. Hence, it is seen that cams 71 and 60 73 being rotatable on the shaft 21 and rotatable relative to each other, may be adjusted by relative movement of the gear wheels 75 and 82 or either cam may be moved independently of the 65 other cam by operation of its own gear wheel.

The brush 72 is pivotally mounted upon the outer end of an arm 84, which constitutes a portion of and extends from the hollow shaft 21. A spring member 85 biases the free end of the brush 70 72 toward the rims of the cams 71 and 73. Inasmuch as the arm 84 constitutes a part of and rotates with the hollow shaft 21 which makes one revolution each day in accordance with the hour hand of the clock, the brush 72 is dragged around 75

the rims of the cams 71 and 73 once each twenty-four hours.

The brush 72 is electrically connected to the arm 84 by a conductor 86 and the arm is grounded to the machine by a brush 87 riveted to the plate 6 in position to slidably engage the underside of the gear wheel 50 when it and the arm 84 rotate with the hollow shaft 21. The contact making cam 71 is provided with a channel 90 in which is disposed one end of a spring brush 91, the other end of which is mounted in an insulated block 92 secured to the corner post 3 by a pair of screws 93. The brush 91 is electrically connected by a conductor 94 to a binding post 95 and the frame 15 is provided with a binding post 96 so that switch 70 may be connected in any circuit which it is desired to control by the time switch.

As shown in Fig. 7 the contact making cam 71 is provided with a shoulder section 96 upon which 20 the brush 72 rides when the time switch is closed, a shoulder 97 and a cutaway portion 98. The cam 73 is provided with a shoulder section 100, a shoulder 101 and a cutaway portion 102. With the cams in the position shown, the brush 72 is 25 held out of engagement with the circuit making cam 71 by the shoulder section 100 of the cam 73. However, when the arm 84 is moved clockwise, the brush 72 slides off the shoulder 101 of cam 73 and into contact with the rim 96 of the 30 cam 71. Hence, the switch is closed during its further operation until the brush 72 reaches the point where it falls off the shoulder 97 of the cam 71 and into engagement with the rim portion 102 of the cam 73 which holds the brush 35 72 out of engagement with the rim of the circuit-making cam 71. Hence it will be seen that relative rotation of the cams 71 and 73 by their operating gear wheels 75 and 82 will lengthen or shorten the time the brush 72 is in contact with 40 the contact making surface 96 of the cam 71 during the daily rotation of the brush by the arm 84. It will also be evident that, when the brush 72 is traveling along the contact making portion 96 of the cam 71, a circuit is completed from the 45 binding post 95 through the conductor 94, brush 91, hub member 77, conducting cam 71, brush 72, conductor 86, arm 84, brush 87, and the frame of the machine to the binding post 96.

Therefore, it is seen that while the brush 72 50 is travelling around the cam members 71 and 73 once each day, the switch is closed during that portion of the time that the brush 72 is in contact with the contact-section 96 of cam 71. During the remainder of the travel of the brush 72, 55 the circuit is open because the brush then rides upon the outer rim of the cam 73 and out of contact with cam 71. Hence the length of time the circuit remains closed may be adjusted by so rotating one or both of the cams as to vary the difference between the position of the shoulder 60 101 of cam 73 and the shoulder 97 of cam 71.

It is also seen that it is the position of the cam 73 which determines when the circuit is turned on and that it is the position of the cam 71 which 65 determines when the circuit is turned off.

The means for adjusting the cam 73 to the time desired for turning on the circuit comprises a gear wheel 106 disposed on a hub 107 (Figs. 2, 3 and 6) rotatably mounted upon a shaft 108 70 having its lower end mounted in the plate 6 and its upper end mounted in the plate 7, and an internal gear wheel 110 mounted on the underside of the gear wheel 106 and spaced therefrom by suitable spacing blocks 109. The inter- 75 nal teeth of the wheel 110 are disposed to engage

a pinion 111 rotatably mounted by a pin 112 upon an astronomical "on" lever 113 one end of which is provided with a hub 114 which is rotatably mounted upon the lower portion of the shaft 108 with its lower end in engagement with the plate 106. The other end of the lever 113 is controlled in movement by an astronomical cam to be described later. The pinion 111 not only engages the internal gear wheel 106 but it also engages a gear wheel 116 which is firmly mounted upon the shaft 108 by means of a pin 117 through its hub portion. 10

As shown, the shaft 108 is provided with a shoulder 121 which is disposed to engage the plate 7 and to be pulled up against that plate 15 by the action of a clutch washer 128 disposed between the face plate 10 and the plate 7. By reason of the friction washer 128, the shaft 108 will stay in the position to which it may be rotated by operating the knob 126. By reason of this 20 construction, the cam 73 may be adjusted to its proper position by operating the hand knob 126 to rotate the shaft 108, which rotates gear wheel 116, which, in turn, rotates the pinion 111 on its pin 112 thereby effecting movement of the inner gear wheel 106. Inasmuch as the gear wheel 106 is attached to the gear wheel 106 by the blocks 109, that gear wheel rotates the gear wheel 75 with which it engages and consequently rotates the cam 73 associated therewith when the knob 30 126 is turned.

The rotation of the cam 73 is designed to adjust the time switch to close at any desired time relative to sunset and as shown in Fig. 1, the knob 126 has disposed upon it a hand or pointer 129 35 which indicates on the dial 130 the "hours after sunset" at which the time switch will close to turn on the lamps when it is adjusted in accordance with the dial.

The means for adjusting the cam 71 to turn 40 off the lamps at a desired period before sunrise comprises a mechanism the same as that described for turning on the lamps at sunset and hence will not be described in detail. This mechanism is indicated broadly by the dial 131 marked 45 "Hours before sunrise", a pointer 132 thereon attached to a knob 133 for operating a shaft 134. This shaft in turn, operates a gear wheel 135 to rotate a pinion 136 mounted on an astronomical "off" lever 140 to be described later. The pinion 50 136 engages and rotates an internal gear wheel 137 mounted on an external gear wheel 138, which, in turn, engages and rotates the gear wheel 82 for adjusting the cam 71.

Hence the time for turning the lamps off just 55 before sunrise may be set by turning the knob 133 to effect the rotation of the gear wheel 82 and the consequent rotation of the cam 71 to such a point that its shoulder or broken away portion 97 will permit the brush 72 to fall into engagement, at the correct time, with the circuit opening cam 71 which keeps the brush from touching the contact cam 71 and thereby turns the lights off at the desired time. 60

Inasmuch as the time of sunset and the time 65 of sunrise vary in accordance with the seasons of the year, I have provided a device for automatically varying the operation of the means for adjusting the time switch cams in accordance with the variations of sunset and sunrise. In 70 order to accomplish this automatic adjustment, the astronomical "on" lever 113 is connected at its outer end by a pivot screw 118 to a link 119, the other end of which is pivotally connected by a screw 120 to an astronomical lever 121, the 75

lower ends of which are pivotally disposed on the plate 1. An astronomical cam disk 122 is mounted upon the clock shaft 15 for controlling the movement of the lever 121, link 119 and the arm 113 in one direction.

A biasing spiral clock spring 124 having one end secured to the hub 114 of the arm 113 and its other end secured to the corner post 5, biases the arm 113 in the other direction and opposite to the pull of the link 119. The cam 122 is rotated in accordance with the yearly rotation of the clock shaft 15 and thereby moves the astronomical lever 121 and link 119 against the action of the spring 124 in accordance with the seasons of the year, thus so controlling the position of the pinion 111 mounted on the arm 113 that it will also change the "on" adjusting device in accordance with the seasons of the year.

The astronomical lever 140 upon which the pinion 136 is supported is pivotally mounted by a hub 140a upon the shaft 134 and is similar to the lever 113, except that its outer end is disposed to engage a roller 141 on the underside of the arm 113, so that movement of the arm 113 by the link 119 will also effect a corresponding movement of the arm 140. The arm 140 is also biased away from the link 119 by a spiral spring 142, one end of which is attached to the corner post 4 and the other end of which is coiled around and attached to the hub 140a. By reason of this construction, the position of the arm and the pinion 136 mounted thereon is adjusted by the movement of the cam disk 122 against lever 121 and the action of the link 119, in accordance with the variations of the times of sunrise and consequently so varies the position of the cam 71 that it cuts off the lamp circuit at the selected time before sunrise each day, in accordance with the seasons of the year.

Heretofore, in constructing astronomical time switches, it has been necessary to provide for each latitude a switch constructed for that particular latitude, so that the switches would automatically follow correctly the variations in the time of sunrise and the time of sunset. This occasioned considerable difficulty by reason of the necessity of making a special machine for each latitude. I overcome this difficulty by so constructing and mounting the cam 122 that the device may be easily adjusted for any latitude, and thus permit the same switch to be operated accurately in any latitude.

In practicing my invention, I provide the cam 122 with a slot 143 and an adjusting block 144. The slot is sufficiently wide and long to permit the shaft 15 to pass through it and to also permit the cam to be moved transversely of the shaft. The block is firmly affixed to the shaft 15 directly underneath the cam, in which position it acts as a support and a position-adjusting means for the cam. A cap bolt 145 passes through the slot 143 and into a screw-threaded aperture in the adjusting block 144. The head of the cap bolt 145 rests upon and engages the upper surface of the cam 122, so that the cam will be firmly held to the adjusting block when the cap bolt is screwed tightly into the adjusting block. The underside of the cam 122 is provided with a latitude scale 148 and the block is provided with a point or mark 146 which cooperates with the scale to indicate the latitude for which the device is adjusted.

In Fig. 9, the adjusting block is shown with its marker 146 disposed opposite the graduation "35" corresponding to latitude 35. In this position, the

cam 122 will operate accurately for latitude 35. If it is desired to have the device operate for latitude 30, the cap bolt 145 may be loosened and the cam moved on block 144 until the marker 146 corresponds to latitude 30 on the scale. The cap screw is then tightened to hold the cam 122 in the position to which it is adjusted. In this position, the cam 122 will cause the machine to operate accurately in latitude 30. Thus it is seen that by loosening the adjusting block 144 and moving the cam thereon until the marker 146 and the latitude marked on the scale 148 agree, and then tightening the cap screw to hold the cam 122 in place, the cam will then cause the machine to operate accurately and automatically for the latitude indicated, thereby doing away with the necessity of providing a different time switch for the various latitudes.

The operation of the timing switch is as follows: The switch and clock are prepared for operation by moving the hour hand 17 against its frictional engagement with the hollow shaft 21 until it is disposed in proper relation to the minute hand 18. The knob 22 is then rotated to set the hour hand and the minute hand to indicate the correct time on the dial 13. This action can take place without disturbing the motor by reason of the frictional engagement between the shaft 20 and the gear wheel 42 operated by the motor.

Next, the knob 23 is rotated to indicate on the dial 12 the correct month and the division thereof corresponding to the time at which the instrument is being set. The operation of the knob 23 also rotates the astronomical cam 122 to the proper position for the time and year indicated by the pointer 14 on the dial 12. This adjusting rotation is permitted by reason of the frictional engagement between the shaft 15 and the gear wheel 63.

The switch 70 is next adjusted for turning on the lamps (not shown) by rotating the knob 126 to cause the arrow 129 to indicate on the dial 130 the time after sunset at which it is desired to light the lamps. This operation rotates the cam 13 to such a position that it will permit the time switch 70 to close the timing circuit represented by the conductors 86 and 94. The next step is to turn the knob 133 and thereby rotate the pointer 132 to that point on the dial 131 which corresponds to the time before sunrise at which it is desired to have the lamps turned off. This operation causes the switch cam 71 to rotate to the point where the circuit will be cut off by the action of the brush 72 at the correct time.

Inasmuch as the clock is now set for operation, the motor 24 is started by connecting it to any suitable source of energy (not shown) and the clockwork begins to run. As the time set for turning on the lights at a predetermined time after sunset approaches (assuming that the clock has been set during the daytime), the brush 72 is rotated around the rings of the cams 71 and 73 to a point where it drops off the shoulder 101 on the contact-breaking cam 73 into engagement with the contact-making portion 96 of the cam 71. The engagement of the brush 72 with the cam 71 completes the circuit through the conductors 86 and 94 for turning on the lamps.

As the night passes and the time at which the lamps are to be turned off before sunrise approaches, the brush 72 is moved around the rim of the cam 71 by the operation of the clock shaft 21 and its arm 84 to a point where the brush falls off the shoulder 97 of the cam 71 and into

engagement with the outer rim 102 of the cam 73, in which position it is held out of engagement with the contact making cam 71 and thereby breaks the circuit through the conductors 86 and 94, thus turning off the lamps.

As the months pass, the operation of the calendar shaft 15 by the clock mechanism rotates the astronomical cam 122 so that that cam, by pressing against the lever 121, moves the link 119 and 10 the levers 113 and 140 in opposition to the pull of the springs 124 and 142, to so adjust the position of the pinions 136 and 111 as to change the position of the switch cams 71 and 73 in accordance with the season of the year. This adjustment 15 will be effected, as shown, by reason of the fact that the gear wheel 116 is firmly disposed on the shaft 108 which is biased by the friction clutch 28 against free rotation; therefore, when pressure is exerted against the pinion 111 by the 20 arm 113, that pinion revolves around the gear 116 and so doing rotates the internal gear 108, which moves the gear 106 to effect rotation of the gear wheel 75, and thereby rotate the cam 73. This changes the time for the time switch to be 25 turned on in accordance with the change in the time the sun sets.

At the same time, the pinion 136 on the arm 140 is revolved around the gear 135 by the arm and thereby causes rotation of the internal gear 30 wheel 137, which effects rotation of the gear wheel 138, thereby rotating the cooperating gear wheel 82 which in turn effects rotation of the switch cam 71 to a point where its shoulder 57 will cause the brush 72 to turn off the lights before sunrise 35 at the time desired in accordance with the season of the year. Hence it is seen that the time switch, after being started, operates automatically without attention for all seasons of the year.

In some cases, it may be desired to adjust the 40 time switch in such manner that it will turn off the lamps at some stated time during the night, say, at one o'clock, and not at a time indicated as so many hours before sunrise. This stated time of one o'clock will not be changed by any variation 45 in the time of the sunrise, and the time switch will not vary it in any way. In order to accomplish this novel result, I have provided a pin 150 on the underside of the arm 140 for cooperation with a latch 151 mounted upon the corner post 4. The scale 131 of the face plate is also 50 provided with an outer scale 152 marked with the hours from 12 to 5 for cooperation with the pointer 132. When it is desired to have the lamps turned off at, say, one o'clock, the pointer 132 is 55 rotated by the knob 133 to the index 1 of the scale 152 and the latch 151 is placed against the pin 150 on the arm 140 to hold the free end of the arm 140 out of engagement with the roller 141 on the underside of the arm 113, regardless 60 of the effect of the biasing spring 142. With the catch disposed against the pin 150, the arm 140 will not be operated by the astronomical cam 122 and its associated levers and will remain stationary against the catch 151. Therefore, when 65 the "off" adjusting means is set at, say, one o'clock, the operation of the clock means will cause the brush 72 to slide off the conducting cam 71 and into engagement with the opening cam 73, at the hour set on the dial 152, regardless of its relation to the actual time of sunrise, thereby turning the lamps off.

It will be apparent that my astronomical time switch may be advantageously utilized to control some power devices directly. However, when a 75 large amount of power is to be controlled, it will

be preferable to utilize the time switch 70 to actuate some relay or electro-magnetic circuit controller (not shown) for controlling such large amount of power. Inasmuch as such relays or controllers are not part of this invention and are 5 old and well known in the art, no description thereof will be given.

By reason of the foregoing illustration and description, it will be seen that I have provided an accurate astronomical time switch which may be 10 used in any section of the country regardless of its latitude and which may be easily and quickly adjusted for many desired conditions in connection with the operation of electrical circuits for 15 lamps or other devices.

Although I have shown and described certain specific embodiments of my invention, many modifications thereof and changes therein are possible. Therefore, my invention is not to be restricted except insofar as is necessitated by the 20 prior art and by the scope of the appended claims.

I claim as my invention:

1. In an astronomical time switch, a clock mechanism for indicating the time of the year including a shaft and means for rotating the shaft 25 on its axis only once each year, a switch, means responsive to operation of the clock mechanism for closing the switch and for opening the switch each day, means for setting the switch to be closed at a predetermined time each day relative 30 to the time of sunset on that day, a cam disk provided with a slot, means fixing the cam disk on the shaft with the shaft extending through the slot to cause the cam disk to be rotated once each year by the rotation of the shaft, means for 35 adjusting the position of the cam disk on the shaft in accordance with the latitude in which the time switch is to be used, a lever, means for biasing the lever against the outer periphery of the cam disk and means responsive to operation 40 of the lever by the rotation of the cam disk for controlling the operation of the switch in accordance with the seasons of the year.

2. In an astronomical time switch, a clock mechanism for indicating the time of year, a 45 switch, means responsive to operation of the clock mechanism for closing the switch and for opening the switch each day, means for setting the switch to be closed at a predetermined time each day relative to the time of sunset that day, means 50 responsive to the operation of the clock mechanism for changing said setting means in accordance with the season of the year, said changing means including a cam provided with a slot in which an operating member of the clock mechanism is disposed, a block firmly affixed to said operating member, a cap screw for fastening the cam to the block, and a cooperating scale and mark on the cam and the block for indicating the 55 latitude for which the cam is adjusted on the block.

3. In an astronomical time switch, a clock mechanism for indicating the time of the year, a switch comprising a brush, a circuit making cam and a circuit opening cam, and means for 65 rotatably supporting the cams in cooperative relation to each other, means responsive to operation of the clock mechanism for moving the brush around the outer rims of the said cams daily, means for biasing the brush toward said rims, 70 said circuit breaking cam being provided with a rim portion extended to prevent the brush from engaging the circuit making cam during one part of its travel and said circuit making cam having an extended portion to prevent the brush from 75

engaging the circuit breaking cam during another portion of its travel, and means for rotating said cams relative to each other for setting the times at which the switch shall be opened and closed during the daily rotation of the brush around the rims of the cams by the clock mechanism.

4. In an astronomical time switch, a clock mechanism for indicating the time of the year, a switch comprising a brush, a circuit making cam and a circuit opening cam, and means for rotatably supporting the cams in cooperative relation to each other, means responsive to operation of the clock mechanism for moving the brush around the outer rims of the said cams at a rate of once each twenty-four hours, means for biasing the brush toward said rims, said circuit breaker cam being provided with a rim portion extended to prevent the brush from engaging the circuit making cam during one part of its travel and said circuit making cam having an extended rim portion to prevent the brush from engaging the circuit breaking cam during another portion of its travel, a setting means for rotatably adjusting the position of the circuit making cam and a setting means for rotatably adjusting the position of the circuit breaking cam to cause the switch to close and to open at predetermined times relative to the times of sunset and sunrise, and means responsive to the operation of the clock mechanism for changing said setting means in accordance with the seasons of the year to automatically preserve the predetermined times of closing and opening the switch relative to the times of sunset and sunrise.

5. In an astronomical time switch, a clock mechanism for indicating the time of the year, a switch comprising a brush, a circuit making cam and a circuit opening cam, means for rotatably supporting the cams in cooperative relation to each other, means responsive to operation of the clock mechanism for moving the brush around the outer rims of the said cams at a rate of once each twenty-four hours, and means for biasing the brush toward said rims, said circuit breaking cam being provided with a rim portion extended to prevent the brush from engaging the circuit making cam during one part of its travel and said circuit making cam having an extended rim portion to prevent the brush from engaging the circuit breaking cam during another portion of its travel, a setting means for rotatably adjusting the position of the circuit making cam and a setting means for rotatably adjusting the position of the circuit breaking cam to cause the switch to close and to open at predetermined times relative to the times of sunset and sunrise, and means responsive to the operation of the clock mechanism for changing said setting means in accordance with the seasons of the year to automatically preserve the predetermined times of closing and opening the switch relative to the times of sunset and sunrise and means for adjusting the position of the changing means in accordance with the latitude in which the switch is to be used.

6. In an astronomical time switch, a clock mechanism for indicating the time of the year, a

switch comprising a brush, a circuit making cam and a circuit opening cam, means for rotatably supporting the cams in cooperative relation to each other, means responsive to operation of the clock mechanism for moving the brush around the outer rims of the said cams at a rate of once each twenty-four hours, means for biasing the brush toward said rims, said circuit breaking cam being provided with a rim portion extended to prevent the brush from engaging the circuit making cam during one part of its travel and said circuit making cam having an extended rim portion to prevent the brush from engaging the circuit breaking cam during another portion of its travel, a setting means for rotatably adjusting the position of the circuit making cam and a setting means for rotatably adjusting the position of the circuit breaking cam to cause the switch to close and to open at predetermined times relative to the times of sunset and sunrise, means for adjusting the position of the setting means comprising means for biasing the setting means toward the position to which they have been adjusted, and a lever and a single astronomical cam responsive to operation of the clock mechanism for moving the setting means against the operation of the biasing means in accordance with the seasons of the year to automatically preserve the predetermined times of closing and opening the switch with reference to the times of sunset and sunrise.

7. In an astronomical time switch, a clock mechanism for indicating the time of the year, a switch comprising a brush, a circuit making cam and a circuit opening cam, means for rotatably supporting the cams in cooperative relation to each other, means responsive to operation of the clock mechanism for moving the brush around the outer rims of the said cams at a rate of once each twenty-four hours, and means for biasing the brush toward said rims, said circuit breaking cam being provided with a rim portion extended to prevent the brush from engaging the circuit making cam during one part of its travel and said circuit making cam having an extended rim portion to prevent the brush from engaging the circuit breaking cam during another portion of its travel, a setting means for rotatably adjusting the position of the circuit making cam and a setting means for rotatably adjusting the position of the circuit breaking cam to cause the switch to close and to open at predetermined times relative to the times of sunset and sunrise, means for adjusting the position of the setting means comprising means for biasing the setting means toward the positions to which they have been adjusted, a lever and a single astronomical cam responsive to operation of the clock mechanism for moving the setting means against the operation of the biasing means in accordance with the seasons of the year to automatically preserve the predetermined times of closing and opening the switch with reference to the times of sunset and sunrise, and means for changing the position of the astronomical cam whereby it will operate for the latitude in which the switch is to be used.

FRANK CONRAD.
